Rand Inc., Buffalo, N. Y., a corporation of Dela-
ware

Application November 1, 1938, Serial No. 238,126

4 Claims.

(Cl. 30—43)

This application relates to mechanical razors and more particularly to the operation and construction of a shearing head therefor.

In mechanical razors of the usual type it has been the general practice to provide a shearing head in which the outer cutter, or shear plate, is held stationary with respect to the handle, while the inner cutter is oscillated with respect to the outer cutter by some form of driving arm. While this type of head has been found satisfactory in use, there is one disadvantage, namely, that the blades or bars of the outer cutter bend or cover a considerable portion of the hairs in the skin traversed. This necessitates the movement of the razor over the skin a number of times to insure that all of the hairs will be cut.

To overcome this disadvantage it is proposed to provide a movable outer cutter, which will have a combing or sifting action, thereby insuring that a major portion of the hair in the skin traversed by the razor will be picked up and cut.

It is, therefore, the principal object of the invention to provide a shearing head in which the outer cutter is moved a short distance relative to the handle, whereby the blades sift and comb the hair into position to be cut.

Another object is to provide an outer cutter which is adapted to be given a slight longitudinal movement relative to the handle and in the same direction as the inner cutter.

A still further object is to provide a resilient cushion, between the driving means and outer cutter for reducing noise and insuring positive movement of the cutter.

A more clear conception of the construction, operation, and further objects of the invention may be had from the following specification when read in conjunction with the accompanying drawings, in which:

Fig. 1 is a side elevation of a shearing head with a portion broken away to disclose the invention;

Fig. 2 is a cross sectional view taken substantially along the line 2—2 of Fig. 1;

Fig. 3 is a longitudinal section through the center line of the head disclosing the resilient driving means;

Fig. 4 is a bottom view of the outer cutter.

A shearing head of this type is well known in the art and is similar in most respects to that disclosed and described in the patent to H. Landsiedel, No. 2,108,493, issued February 15, 1938.

Shearing heads of this character are composed of an outer cutter 10 secured to a handle 11, of

any well known plastic material such as bakelite, in which is mounted any suitable mechanism adapted to oscillate a driving arm 12. It is obvious that the arm 12 may be oscillated by a number of mediums such as an electric motor, a spring motor, a flexible shaft, or manually operated levers similar to the well known type of hair clippers. Positioned in and guided by the outer cutter is an inner cutter 14 having a slot 19 in the base thereof with which the driving arm cooperates.

The outer cutter has heretofore been fastened to the handle by a set screw 15 and was held from longitudinal movement by a lug 16 on the handle engaging a slot in the base of the outer cutter.

In the present invention the same means is provided with the following difference, i. e., that the set screw 15 only prevents vertical movement of the outer cutter and the lug 16 no longer prevents longitudinal movement, but is used as a limit stop to permit a slight oscillation of the outer cutter.

Referring to Fig. 1, it will be noted that a slot 17 is formed in the base of the outer cutter 10 and there is positioned in the slot a tapered channel-shaped block 18 of resilient material, such as rubber or the like. It is obvious that a piece of spring metal of suitable shape could well be substituted for the rubber block.

The set screw 15 (Fig. 2) is formed with a reduced tip portion 20 which is adapted to enter and cooperate with a longitudinal slot 21 (Fig. 1) cut in the outer cutter 10. The screw 15 is of such a length that the tip 20 thereof prevents vertical movement of the outer cutter but does not reach the bottom of slot 21 and hence will not bind to prevent longitudinal travel of the cutter. In other words, the reduced tip 20 engages the slot 21, and provides a track for the cutter 10.

The shearing head in this type of razor is inserted in a longitudinal groove 22 in the top of the handle. In the present embodiment, a cushion 23 of some easily deformable, yet resilient, material, such as rubber is positioned in the bottom of slot 22. This cushion provides a means whereby any manufacturing errors in the locating of the slot 21 can be corrected to insure the free movement of the end of screw 20 in the slot 21. The deformable property of the rubber insures that the cutter will move easily with respect to the bottom of the groove 22.

The driving arm 12 for the inner cutter extends through a slot 24 in the base of the outer cutter and in razors heretofore known in the art this slot was formed sufficiently long to per-

mit free oscillation of the arm 12. In the present embodiment, however, a plug 26 of resilient material similar to the block 18 is inserted in an enlarged portion of each end of the slot and is 5 of sufficient size so that the arm 12 will come in contact therewith just prior to the end of the stroke.

Spring-pressed pins 27 are provided in the handle 11 which extend through the base of shear plate 10 and contact the base of inner cutter 14, 10 pressing it into shearing relation with the shear plate.

In assembling, the shearing head is inserted in the groove 22 and pressed down on the cushion 15 23 until the tip 20 of the screw 15 can enter the slot 21. The head is positioned with the lug 16 in the resilient block 18 and arm 12 passes through the slot 24 in the base and engages the slot 19 in the inner cutter 14.

20 In operation any oscillation of arm 12 will drive the inner cutter longitudinally. Due to the frictional engagement between the inner cutter and the outer cutter, it is caused to move a short distance longitudinally against the resilient action 25 of the block 18 and the deformation of cushion 23. As soon as the friction is overcome, the outer cutter is returned toward normal by the resilient action of block 18 and cushion 23 until just prior to the end of the stroke of arm 12, at which 30 time the outer cutter is again moved longitudinally, due to the contact of the arm block 26. The relative amount of movement of the outer and inner cutters is indicated by the dotted lines in Fig. 3. While the movement of the outer cutter, due to the frictional contact between the cutters is slight and may vary, the movement, 35 due to the arm 12, is always approximately uniform.

From the above operation, it will be apparent 40 that the outer cutter will have a slight movement relative to the handle which will cause the hair to be sifted or combed in between the blades of the shear plate where they will be cut by the inner cutter.

45 While I have described what I consider to be a highly desirable embodiment of my invention, it is obvious that many changes in form could be made without departing from the spirit of my

invention, and I, therefore, do not limit myself to the exact form herein shown and described, nor to anything less than the whole of my invention as hereinbefore set forth, and as herein-after claimed.

What I claim as new, and desire to secure by Letters Patent, is:

1. In a mechanical razor, a handle, a shear plate mounted for longitudinal movement on said handle, an inner cutter cooperating with said 10 shear plate, an arm for reciprocating said inner cutter, and resilient means in the base of said shear plate compressed by said arm for reciprocating said plate longitudinally of said handle.

2. In a mechanical razor, a handle, a shear 15 plate mounted for longitudinal movement on said handle, a resilient mounting for said shear plate adapted to restrict said longitudinal movement, an inner cutter cooperating with said shear plate, an arm for reciprocating said inner cutter, 20 and resilient means in the base of said shear plate compressed by said arm for reciprocating said shear plate longitudinally of said handle.

3. In a mechanical razor, a handle, a shearing head mounted on said handle, said shearing head 25 comprising a shear plate and inner cutter each adapted to reciprocate longitudinally with respect to each other and said handle, a lug on said handle, a slot in the base of said shear plate, and a resilient cushion in said slot engaging said 30 lug to limit the longitudinal movement of said plate with respect to said handle.

4. In a mechanical razor, a handle, a detachable shearing head comprising inner and outer cutter members mounted for longitudinal reciprocation with respect to each other and said handle, a longitudinal slot in the base of said outer cutter, a shouldered screw in said handle adapted to engage said slot to permit longitudinal movement of said outer cutter, said screw preventing 40 detachment of said outer cutter from said handle, a lug on said handle, a second slot in the base of said outer cutter, and a resilient cushion in said slot engaging said lug to permit limited longitudinal movement of said outer cutter with 45 respect to said handle.
